UNITED STATES PATENT OFFICE.

HEMAN OSBORNE, OF SPRINGFIELD, MASSACHUSETTS, ASSIGNOR OF ONE-HALF TO CHARLES P. CHASE, OF SPRINGFIELD, MASSACHUSETTS.

SHUTTER-WORKER.

SPECIFICATION forming part of Letters Patent No. 722,878, dated March 17, 1903.

Application filed January 16, 1902. Serial No. 90,003. (No model.)

To all whom it may concern:

Be it known that I, HEMAN OSBORNE, a citizen of the United States of America, and a resident of Springfield, in the county of Hampden and State of Massachusetts, have invented 5 certain new and useful Improvements in Shutter-Workers, of which the following is a full, clear, and exact description.

This invention relates to improvements in shutter-workers of that class comprising a worm-wheel having on its arbor or shaft a lever connected with the shutter, a worm-shaft having a worm in mesh with the worm-wheel, and connections accessible at the interior of 10 the room for rotating the worm-shaft, causing the swinging of the shutter to an open or closed or an intermediate position, the mechanism of this character, as well known, having the capability of retaining the shutter in 15 any given set position. Shutter-workers of this class have been considered more advantageous generally than other descriptions of shutter-workers, although they have, nevertheless, been open to the objection of being 20 somewhat cumbrous, requiring nice and careful setting up and fitting on and within the window-casing and have contained in the details comprising the worm-gearing, the inclosing-casing therefor, and the various connections 25 a greater number of parts than have been really desirable, and, moreover, the aspect of the device has not been altogether 30 slightly and pleasing.

The object of this invention is to provide 35 a shutter-worker which is entirely successful, satisfactory, and efficient in operation, comprising the fewest possible number of essential parts, and which parts are so constructed, arranged, and combined as to be inexpensive 40 of manufacture, easy of assemblage, capable of ready application on and through the window-casing and in connection with the shutter, and constituting in no manner an object 45 of objection because of its general aspect.

The invention consists in a shutter-worker mechanism embodying novel details of construction and combinations of parts, all substantially as hereinafter fully described, and set forth in the claims.

The improved shutter-worker is illustrated 50 in the accompanying drawings, in which—

Figure 1 is a vertical sectional view through a portion of the window-casing at which the device is applied, through a portion of the shutter-worker, and a portion of the blind or 55 shutter operatively engaged thereby. Fig. 2 is a horizontal sectional view showing the above-mentioned parts, the blind or shutter being shown in plan view, and the line of section on which this view is taken is indicated 60 at 2 2, Fig. 1. The section-line 1 1 on Fig. 2 more definitely indicates the line of section for Fig. 1. Fig. 3 is a perspective view showing a two-part casting constituting the support and inclosure for important working 65 parts of the device. Fig. 4 is a rear view of the principal one of the said two-part casting, showing the inwardly - extending integral journal - lugs thereof, and the worm and sprocket-wheel shaft mounted in said lugs 70 in section, as taken on the line 4 4, Fig. 2. Fig. 5 illustrates the detail construction of a sheave-containing bushing forming a part of the novel device, comprising, respectively, a rear view, an axial sectional view, and a front 75 view of the bushing and sheave. Fig. 6 represents in perspective the slotted plate to be fastened on the upper portion of the blind and the formation of the extremity of the lever of the shutter-worker which engages said 80 slotted plate. Fig. 7 is a perspective view of the aforementioned sheave-containing bushing, showing the adaptability thereof for receiving a peculiar key or wrench for screwing the bushing within the inner side of the 85 window-casing in the setting up of the shutter-worker devices.

Similar characters of reference indicate corresponding parts in all of the views.

In the drawings, A represents the casting 90 constituting the casing and support for the worm-wheel B, the shaft C having thereon both the worm D, which engages the worm-wheel, and the sprocket-wheel E, by means of which, through chain F, the shaft is rotated. The said casting comprises the separable portions a and a³, and the portion a consists of the flat plate 10, having the screw-holes 12, by which to screw it on the outer side of the window-casing, the outwardly-extending hood-like portion or half-shell 13, with the opposite lugs 14 14, having the hole 95 100

or aperture 15 therethrough and having the inwardly-extended integrally-cast lugs or ear-pieces 16 16, which constitute the journal-supports for the shaft for the worm and 5 sprocket-wheel. The other member of the two-part casting is in the form of a shell having ear-lugs 14^a 14^a, so that when this half-shell α^2 is matched with and under the other half-shell and secured by the screws 17 17, 10 passed through the said matching lugs 14 and 14^a, a complete and tight inclosure is provided for the worm-wheel, the axially-vertical journals of which have bearings for rotation in the socket 18 within the top of the upper 15 per-half-shell 13 and through the journal-hole 19 in the lower half-shell, the said worm-wheel having the hubs 20 20 within the journal members, the ends of which hubs engage the upper and lower walls of the casing and maintain 20 the worm-wheel steady in its proper position.

The shaft C is of about a length corresponding to the space between the journal-lugs 16 16, and the worm D is integrally cast as a 25 part thereof, as is practicable of performance; but the sprocket-wheel E is forced with a driving fit, being separately made on the end portion of the said shaft. Said shaft is axially drilled within its ends, and when brought 30 to alignment with the perforations 22 in the journal-lugs 16 the separately-provided straight round journal-studs 23 23 are passed loosely through the perforations of the journal-lugs, in which they have their bearings 35 for rotation and with a tight driving fit into the holes drilled in the worm-shaft casting.

The casing, screwed upon the outside of the building, has the lugs 16 16 and the worm and sprocket and their shaft journaled in said 40 lugs projecting into a mortise α , the meshing of the worm with the worm-wheel being permitted by the provision of the aforementioned aperture 15 in the face-plate 10 of the casing.

45 The lower journal of the worm-wheel, which is extended down, through, and below the casing at the exterior of the building, has rigidly affixed thereto the horizontal lever G, of suitable length, the lower extremity of which is 50 downwardly turned and formed with the neck 25 and enlargement 26 therebelow, and this neck downturned extremity of the lever engages in and through the slot 27 in the horizontal member 28 of an angular plate d, the 55 vertical member 29 of which is screwed to the face of the blind. This connection permits the lever to be swung and the blind to be swung thereby with all ease and freedom, doing away with the necessity of a link connected to the lever and a bushing-piece secured to the blind, with which the link is engaged, and requiring less labor in setting up the device.

60 A single sprocket-chain J has an intermediate portion thereof arranged in the form of a loop and engaging the sprocket-wheel, and the two courses of this chain thence extend

forwardly through the hole or opening γ thereto in the window-casing through the sheave-containing bushings L L, the chains having 70 rolling contact over the tops of the sheaves γ and hang therefrom downwardly on the face of the window-casing within the room for convenient grasp, being properly guided by the said sheaves. One extremity of the chain 75 when downwardly drawn will operate the shutter-worker to open the shutter, and the other extremity serves as the medium of connection for closing the shutter. The said sheave-containing bushings are constructed 80 in the form of tubular castings externally screw-threaded, and the sheaves are placed therein with their axes at right angles to the axes of the bushings, the journal-rods f^2 on which the sheaves have rolling supports being driven through the opposite walls of the bushing-tubes. The tubular bushings at their outer ends are internally thickened, as indicated at i , so that the outer-end opening of each bushing is of squared form and 90 adaptable to receive the correspondingly-formed prongs z of the wrench or key (shown in Fig. 7) to facilitate the screw engagement of the bushings in holes bored therefor in the front of the window-casing. When these 95 bushings are screwed in flush with the front of the casing, they do not disfigure the interior finish of the room.

Inasmuch as the chain has a tendency to jump and buckle in and relatively to its engagement with the sprocket-wheel and irrespective of whether the two courses of the chain are carried to the bushings arranged in a horizontal line, as indicated in Fig. 2, or arranged one over the other, as they may be, 105 if preferred, I provide as an expedient to prevent the jumping and buckling of the chain and the rendering inoperative of the device a simple metallic ring m, which straddles loosely over the two courses of the chain 110 more or less near to the sprocket-wheel and which is surprisingly efficacious and adequate in its chain-constraining effect and which serves the desired purpose fully while other apparently more manifest expedients 115 to the desired end have failed.

Having thus described my invention, what I claim, and desire to secure by Letters Patent, is—

1. In a shutter-worker, in combination, a 120 casting comprising a face-plate, having an external, downwardly-open, half-shell, an aperture, and rearwardly-projecting journal-lugs, the separable lower half-shell secured at the outer side of the face-plate and to 125 match with the aforementioned half-shell, and having, therewith, journal-sockets, and the worm-wheel the arbor of which is journaled in and through said sockets, and has at its lower end the lever having an operating connection with the shutter, the shaft journaled between said lugs across said aperture, and having the sprocket-wheel and the worm which meshes said worm-wheel through said 130

aperture, the chain, an intermediate looped portion of which encircles the sprocket-wheel, and a pair of sheaves for application at the inner face of the window-casing to and over which the chain is extended from above and below the sprocket-wheel, substantially as described.

2. In a shutter-worker, in combination, a single casting comprising a face-plate 10 having an external, downwardly-open half-shell 13 with the lugs 14, an aperture 15 and rearwardly-projecting journal-lugs 16, 16, the separable lower half-shell having the lugs 14^a to match with the aforesaid lugs 14, and both shells having the journal-sockets 18, 19, and the worm-wheel, the arbor of which is journaled in and through said sockets, and has at its lower end the lever adapted for operating connection with the shutter, the shaft C journaled between said lugs across said aperture, and having the sprocket-wheel, and the worm which meshes said worm-wheel through said aperture, the chain, an intermediate looped portion of which encircles the sprocket-wheel, and means for guiding the two outer portions of the chain through and to the interior of the window-casing, substantially as described.

3. In a shutter-worker, the combination with the casing, a worm-wheel and worm-shaft therewithin, said shaft having a sprocket-wheel thereon and the worm-wheel having on its arbor the shutter-operating lever, of a chain, an intermediate looped portion of which engages around the sprocket-wheel, and double chain-guiding devices each consisting of an externally-screw-threaded tube having a sheave journaled therein and having its outer end opening of squared formation for the reception therein of a key, substantially as described.

4. In a shutter-worker, in combination, the casing, the worm-wheel journaled therewithin and having connected thereto the shutter-operating lever, the shaft having the worm

and a sprocket-wheel, the sprocket-chain, an intermediate loop of which is passed around the lever, means for guiding the opposite courses of the chain in proximity to and through the window-casing and a ring encircling the two courses of the chain within the window-casing, and between the sprocket-wheel and the chain-guiding sheaves f, substantially as and for the purpose described.

5. In a shutter-worker, in combination, a casting comprising a face-plate having an external, downwardly-open, half-shell, an aperture, and rearwardly-projecting journal-lugs 16, 16, the separable lower half-shell secured on the outer side of the face-plate and to match with the aforesaid half-shell, the arbor of which is journaled in and through said sockets, and has at its lower end the lever adapted for operating connection with the shutter, the shaft mounted between said lugs 16 across said aperture, and having the axial holes drilled within its two ends, the journal-studs 23, 23, passed loosely through perforations therefor in the lugs 16, and with a tight driving fit into the said axial holes in the shaft, having the sprocket-wheel, having a driving fit on the said shaft and the worm; which meshes said worm-wheel through said aperture, formed integrally with said shaft, the chain, an intermediate looped portion of which encircles the sprocket-wheel, and a pair of sheaves for application at the inner face of the window-casing to and over which the chain is extended from above and below the sprocket-wheel, substantially as described.
